GOVERNOR MECHANISM

Elmer E. Woodward, Rockford, Ill., assignor to Woodward Governor Company, Rockford, Ill., a corporation of Illinois

Application March 1, 1935, Serial No. 8,908

17 Claims. (Cl. 264—14)

This invention relates to governors of the hydraulic type and the general object is to provide such a governor which is simple in construction, easy to adjust while in operation, and capable of responding more quickly to speed changes and correcting such changes more rapidly than prior governors of the same type.

Another object of the invention is to provide a novel form of governor control mechanism in which the static friction between the parts is minimized and in which the operating characteristics are improved in other respects so that the device responds quickly and accurately.

Still another object of the invention is to provide a governor control mechanism of such character that its speed setting adjustment may be readily manipulated while the device is in operation despite the inclusion in the mechanism of relatively rotatable fluid control valve elements, which valve elements are maintained in constant relative rotation during the operation of the device.

The invention also resides in various structural improvements in governor control mechanisms by means of which accurate and precise governor operation is achieved in an extremely compact, simple and rugged construction.

The invention is illustrated in the accompanying drawings in which—

Fig. 1 is a hydraulic circuit of the automatic governor control showing everything more or less diagrammatically;

Fig. 2 is a longitudinal section through the governor unit;

Fig. 3 is a horizontal cross-section on the line 3—3 of Fig. 2;

Figs. 4 and 5 are sectional details in vertical planes on the correspondingly numbered lines of Fig. 2, and

Figs. 6 and 7 are horizontal sections in the same plane, Fig. 6 looking down upon the seat on the engine block for the governor unit, and Fig. 7 looking up at the bottom of said unit.

The governor constituting the present invention is particularly adapted to meet the exacting requirements of an automatic mechanism for adjusting the pitch of an airplane propeller. Accordingly, the invention has been shown and will be described herein as applied to such use. It is to be understood, however, that I do not intend to limit the invention by such disclosure but aim to cover all modifications and alternative constructions falling within the spirit and scope of the invention.

Referring to Fig. 1, a propeller pitch adjust-

ment mechanism has been shown in which 8 is the crank shaft on the forward end of which a piston 9 is mounted, received in a working cylinder 10 arranged to reciprocate relative to the piston. Forward movement of the cylinder is secured by supplying oil under pressure through the passage 11 provided in the crank shaft extending from a collector ring 12 forwardly through the piston 9, as indicated. The cylinder has arms 13 projecting therefrom working in cam slots 14 on the counterweights 15 attached to the blades 16 in the well known way, whereby to turn the blades to a position of less pitch in the forward movement of the cylinder, each of the counterweights being moved inwardly toward the crank shaft axis. Contrariwise, when oil is allowed to escape from the cylinder 10 through the passage 11 so that the cylinder 10 is free to move rearwardly, the counterweights 15 move outwardly away from the crank shaft axis under centrifugal force and accordingly cause the blades 16 to move to a higher pitch position.

In applying the present governor to the control of the pitch of a propeller, the flow of pressure fluid to and from the servo cylinder is controlled by an automatically operable valve 17, the position of which is controlled by a fly-ball governor 18, whereby in the speeding up or slowing down of the engine the governor valve produces automatically the required change in propeller pitch, so as to maintain substantially constant speed. The governor is suitably driven in proportion to the engine speed. In this case 19 is the drive shaft for the governor 18, driven, as indicated at 19a and 20, directly off the crank shaft 8. 21 is a gear pump, the driving shaft 8a of which may be an extension of the crank shaft 8 or a jack-shaft driven thereby, so that the pump 21 is driven continuously in the operation of the engine. This pump is the engine lubricating pump and draws oil from the sump 22 through a pipe 23 and delivers it at a substantially constant pressure through a pipe 24 to the bearings to be lubricated, a constant pressure of say 85 lbs. being assured by the pressure relief valve 25 arranged to discharge into the sump 22, as indicated. 26 is another gear pump whose driving shaft is the shaft 19 previously mentioned, the pump 26 being shown turned through 90° into the plane of the shaft 19 for the sake of a clearer understanding of the operation, this being a diagrammatic view. The pump 26 will hereafter be referred to as the booster pump to distinguish it from the engine lubricating pump 21 and because it is supplied with oil, as at 27,

under the lower pressure delivered from the pump 21 and in turn delivers the oil under a higher pressure of say 115 lbs. through passage 28 to the governor valve 17. A constant pressure is maintained on the discharge side of the pump 26 by a pressure relief valve 29 arranged to discharge, as at 30, back into the intake of the pump 26.

Referring to Fig. 2, the governor valve 17 comprises a body 31 formed as a boss cast integral with the bottom of the cup-shaped housing 32 of the governor 18. The boss 31 is also recessed at the bottom, as at 33, to provide cavities for the reception of the intermeshing gears 34 and 35 of the booster pump 26. The gear 34 is keyed or otherwise fixed to the shaft 19 to turn therewith and communicate rotation to its companion gear 35. A face plate 36 doweled to the bottom of the boss 31, as at 37 (Fig. 7), closes the gear cavities and is fastened in place suitably by a single screw 38 to complete the governor unit assembly. This unit embodying the governor 18, valve 17, and booster pump 26, is arranged to be demountably secured upon a seat 39 provided therefor on a convenient part 40 of the engine block. Four cap screws 41 serve to fasten the unit in place so that the hexagonal end 42 of the shaft 19 is coupled to the engine driven shaft 19a by entry in the hexagonal bore 43 formed in the latter, and so that ports 44 and 45 in the seat 39 communicating with a passage 27 extending from the engine lubricating pump 21 will communicate with ports 44a and 45a, respectively, provided in the face plate 36, and, at the same time, another port 46 provided in the seat 39 and communicating with a passage 47 leading to the collector ring 12 will be placed in communication with a port 46a in the face plate 36. The port 44a, as appears in Fig. 4, is interconnected with a port 44b through a passage 48 in the face plate 36, and there are two ports 48a and 48b at opposite ends of this passage opening to the top surface of the face plate. A plug 49 closes the port 48b. The port 48a communicates with a passage 50 on one side of the pump gears 34-35 which would communicate with a transverse passage 51 were it not for the plug 52 which cuts off such communication. However, another passage 53 on the other side of the pump gears communicates with the passage 51. The latter has a transverse pressure port 54 extending in opposite directions therefrom for communication with an external annular groove 55 in the shaft 19 and also with the pressure relief valve 29. The shaft 19 has a longitudinal bore 56 in which the stem or plunger 57 of the governor valve 17 is reciprocable, and there are radial holes 58 establishing communication between the bore 56 and the groove 55, as shown. From this description, it should be clear that oil under the lower pressure delivered from the pump 21 through passage 27 is conducted through ports 44 and 44a to the passage 48 in the face plate 36, and from there through port 48a into passage 50 on one side of the pumping gears. The booster pump delivers the oil under higher pressure to the passage 53, from where it is conducted through passage 51 and port 54 to the valve 17. Now, a tubular stub shaft 59 is received in registering bores in the boss 31 and face plate 36, and provides a passage 30 arranged to communicate with the pressure port 54 when the relief valve 29 opens against the action of its spring 60. The passage 30 communicates with a port 30' in the bottom of the face plate 36, which, as shown in Fig. 7, communicates with the port

45a, previously mentioned, as well as with another port 45b. Hence, when the relief valve opens, oil is by-passed through passage 30, ports 30' and 45, to the passage 27, communicating, as previously stated, with the intake side of the booster pump 26. Reciprocal ports are provided, numbered 44b, 45b and 48b, so as to permit easily converting the booster pump from right to left hand operation, or vice versa. The booster pump is illustrated in Fig. 4 with the parts thereof arranged for left-hand rotation of the shaft 19, the plug 49 being inserted in port 48b and the plug 52 closing the top of passage 50. However, for right-hand rotation of the shaft 19, one must transfer the plugs 49 and 52 so as to close the port 48a instead of 48b, and close the upper end of passage 53 instead of passage 50. The plug 52' is interchangeable with the plug 52. The interchangeability of the pump afforded by reciprocal ports also necessitates the provision of a reciprocal port 48b for the port 46a, because, in a reversed arrangement, the passages 27 and 47 (Fig. 6) would, of course, be reversed from the relationship shown. The ports 46a and 46b both communicate with a discharge passage 61 communicating with an annular groove 62 in the passage 19. The groove communicates with the bore 56 through radial holes 63, whereby to establish communication between the governor valve 17 and the passage 61.

The plunger 57 of the governor valve 17 is annularly reduced at a and b and has the portions c and d fitting with a close working fit in the bore 56, and the end portion e sufficiently reduced to leave an annular space around it for free passage of oil through the bore and out to the sump 22 directly through the open end 56' of the bore and also through a radial hole 64 communicating with the annular space 65 in the seat 39 from which oil is drained to the sump 40 through another hole 66. The "lands" c and d having the same annular area exposed to the pressure of the oil from port 54, it is manifest that the valve plunger 57 is balanced and can therefore be moved easily by the governor. Upward movement, as will presently appear, goes with increased engine speed, and, in that event, the holes 63 are uncovered more or less according to the extent of movement of the plunger 57. Oil will, therefore, escape from the passage 61 through the bore 56 to the sump. This oil comes from the working cylinder 10 of the controllable pitch propeller, as follows; through the passage 11 to the collector ring 12, and thence through passage 47 to the port 46 and through 58 registering port 46a to passage 61, and thence through annular groove 62 and holes 63 to the bore 56, and thence to the sump 22. The oil is forced out of the cylinder under the action of the centrifugal weights 15 which simultaneously turn the blades 16 to a position of greater pitch. On the other hand, the plunger 57 is given downward movement in the event of decreased engine speed, and, under those conditions, oil under pressure from the port 54 is delivered through the holes 63 and annular groove 62 to the passage 61 and finds its way through the circuit just outlined to the cylinder 10, and moves said cylinder outwardly against the action of the counterweights 15 and changes the blades 16 to a position of less pitch.

The governor 18 has its cup-shaped housing 32 closed by a cover 67. Weights or "fly-balls" 68 are revolved in the housing 32 with a head 69 that is fixed on the upper end of the shaft 19.

so that the latter serves to drive the governor as well as constituting one element of the valve 17. The weights are pivoted, as at 10, on said head. A coiled compression spring 11 acts normally to urge the plunger 57 of the valve 17 downwardly and at the same time force the weights 68 inwardly, but the weights are arranged to move outwardly under centrifugal force against the action of the spring to move the plunger 57 upwardly. A ball bearing 72 is carried on the upper end of the plunger 57 with its inner race clamped to the plunger by a nut 73, which at the same time provides a seat 74 for the lower end of the spring 11. The weights 68 have fingers 15 which bear against the outer race of the bearing 72. With this construction it is obvious that the head 69 and weights 68 are free to revolve relative to the plunger 57 and spring 11, and that the plunger will move upwardly against the action of the spring 11 when the weights are thrown outwardly under centrifugal force with increased engine speed. The outward movement of the weights is limited by the engagement of projections 76 on the pivot portions of the weights 25 with the head 69, so that the weights will not come into contact with the side wall of the housing 32.

The cover 67 has a hollow cylindrical boss 77 in which a plunger 78, bearing on the upper end 30 of the spring 11, is slidable. The plunger has rack teeth 79 formed in one side thereof, and a pinion 80 meshes with said rack and is arranged to be turned by means of a lever 81 oscillated manually through a suitable push-pull cable (not shown) 35 connected with a knob or control lever operated by the pilot in the cockpit, or pilot's compartment. Depression of the plunger 78 obviously increases the spring pressure upon the plunger 57 so that a higher engine speed is 40 required to move the weights 68 outwardly to bring the plunger 57 to a given position, and vice versa. This control furthermore enables the pilot to move the plunger 57 downwardly positively in the event the spring 11 does not 45 exert sufficient pressure to overcome a tendency on the part of the plunger to stick or bind in the bore 56. A pin 82, extending through the plunger 78, has heads 83 and 84 at its opposite ends, the head 84 being received in a chamber 50 in the nut 73 on the upper end of the plunger 57. This headed pin does not interfere in any way with depression of the plunger 78 or raising thereof to a certain limit, but serves to provide a positive connection between the plunger 78 55 and the plunger 57 to enable the pilot to positively raise the plunger in the event it sticks and the weights 68 fail to move the same. It is apparent, therefore, that while the governor serves to automatically operate the valve 17, the 60 pilot can at any time adjust the governor manually to change to a higher or lower critical engine speed, and in the event of a mechanical trouble arising in the governor, the pilot can manipulate the valve 17 by hand in either direction. Any oil leaking along the plunger 57 and shaft 19 upwardly into the housing 32 is drained 65 through the holes 85 and 86 into the recess 65 and thence through holes 66 to the sump.

In operation, when the engine is started, the 70 weights 68 turn at such a slow speed that the passage 61 is in open communication with the passage 51 so that oil under pressure will be supplied to the working cylinder 10 to decrease the pitch of the propeller. In that way, since 75 the load is lessened, the engine will speed up,

and the engine promptly attains a desired speed. As the engine speeds up, the weights 68 move outwardly under centrifugal force and raise the plunger 57 of the governor valve 17 so as to close the holes 63 and cut off communication 5 with the source of oil pressure—at the same time sealing the working cylinder against loss of oil, whereby to maintain the pitch adjustment. The pitch adjustment remains the same so long as the load on the engine is balanced against the 10 power output of the engine and the speed remains uniform at a given throttle setting. The aim is to keep the engine turning at a constant speed nearest its rated R. P. M. and power output. That speed, which may be referred to as the 15 critical speed, depends upon the pressure exerted by the spring 11—with a light spring pressure which permits the weights 68 to move outwardly under centrifugal force more readily than with a heavy spring pressure, a lower critical 20 speed will be maintained, and contrariwise with heavier spring pressure a higher critical speed will be maintained. The pilot can adjust the spring pressure to suit conditions by merely manipulating the lever 81. Ordinarily the spring 25 pressure will be increased for take-off purposes, because, under those circumstances, or for that matter in any steady climb, the engine should be operated at a speed at or somewhat above its rated R. P. M. for best efficiency. On the 30 other hand, the spring pressure may be lessened for cruising, because then the engine will ordinarily be operated at or somewhat below its rated R. P. M. The adjustment of the lever 81 by push-pull cable control from the cock-pit 35 can be attended to by the pilot very easily. This same control serves as a safety, inasmuch as it enables the pilot to positively operate the governor valve 17 one way or the other in the event the governor weights 68 fail to move the plunger 40 57 upwardly, or the spring 11 fails to move the plunger downwardly. In other words, the automatic control can, at will, be converted into a manual control, so that there is nothing which could possibly mean a hazard for the pilot in the 45 operation of his ship. When the ship is in flight, the governor valve will move up and down repeatedly as increases and decreases of engine speed must be checked. If, due to a change in altitude of the ship, let us say into a dive, the load upon 50 the engine is decreased and it accordingly tends to speed up, the weights 68 move outwardly and raise the plunger 57 to allow oil to escape from the working cylinder 10. The counterweights 15 thereupon immediately move the blades 16 to a 55 position of increased pitch and the speed of the engine is promptly brought back to normal. The plunger 57 quickly resumes its position covering the holes 63 when the speed of the engine gets back to normal, so that the new pitch adjustment 60 is maintained because the working cylinder 10 is sealed. The engine cannot under any circumstances, therefore, have excessive speeding, as would otherwise occur in a dive. On the other hand, when the ship levels off again so that the 65 load upon the engine is increased, there is a decrease in engine speed momentarily, and the movement inwardly of the weights 68 allows the spring 11 to move the plunger 57 downwardly to place the holes 63 in communication with the 70 pressure port 54, so that oil is supplied under pressure to the cylinder 10 so as to decrease the propeller pitch and allow the engine to regain its normal speed. Here again, the plunger 57 promptly returns to its position covering the holes 75

63 to seal the working cylinder and maintain the propeller pitch adjustment. If the ship then goes into a climb so that the load upon the engine is further increased, it follows that a 5 further automatic adjustment of the propeller pitch will occur and the engine will be allowed to operate at its normal speed. In a multi-mo-10 tored ship, where the failure of one engine im-poses greater load upon the other engine or engines, the slowing down results in an automatic change in pitch adjustment similarly as just described, and the other engine, or engines, are not overloaded. Under all circumstances, each engine is operated at its peak efficiency—15 turning constantly at its rated R. P. M. with its propeller pitch always adjusted so that the load balances the power output.

The governor above described is extremely sensitive to speed changes and operates rapidly to 20 correct for such changes by adjusting the speed regulator which in this instance is the propeller adjusting mechanism. This improved action is due to the substantial elimination of static friction between the relatively moving parts of the 25 valve 17. This is accomplished by rotation of the ported sleeve 19 thereby eliminating static friction between this sleeve and the plunger 57. The latter and the speeder spring 71 are not rotatable owing to the fact that there is greater 30 torsional friction between the spring and the adjusting rack 78 than there is in the parts of the ball thrust bearing 72. As a result, no friction is introduced as an incident to provision for manual adjustment of the speeder spring 35 while the governor is in operation so that the plunger 57 is freely shiftable in response to changes in the positions of the flyweights, the governor being thereby rendered very sensitive.

I claim:

40 1. A governor control mechanism comprising a valve chamber, rotatable flyweights, a hollow shaft rotatable with said flyweights and extending into said chamber and having spaced ports therein, a normally non-rotatable valve stem disposed in said shaft and controlling said ports by relative reciprocation between the stem and said shaft, a fluid servo motor, a conduit between said valve chamber and said motor, and other conduits between said valve chamber and a source 45 of pressure fluid supply and a drain receptacle.

50 2. A governor control mechanism, comprising a valve chamber, a hollow drive shaft extending through said chamber and having spaced valve ports therein, a valve stem reciprocable in said hollow drive shaft, a coiled governor spring bearing on one end thereof tending normally to move it in one direction relative to the ports while holding it against rotation with said shaft, governor flyweights turning with said shaft relative 55 to said stem and spring adapted to move the stem in the other direction relative to the ports, a fluid motor, a conduit between said valve chamber and said motor, and other conduits between said valve chamber and a source of pressure fluid supply and a drain receptacle.

60 3. A governor control mechanism, comprising a valve chamber, a hollow drive shaft extending through said chamber and having spaced valve ports therein, a valve stem reciprocable in said hollow drive shaft, a coiled governor spring bearing on one end thereof tending normally to move it in one direction relative to the ports while holding it against rotation with said shaft, governor flyweights turning with said shaft relative 65 to said stem and spring adapted to move

the stem in the other direction relative to the ports, manually adjustable means for adjusting said spring while holding it and the stem against turning, a fluid motor, a conduit between said valve chamber and said motor, and other conduits between said valve chamber and a source of pressure fluid supply and a drain receptacle. 6

4. A governor control mechanism, comprising a body having a chambered portion, a hollow shaft 10 rotatably mounted in a bore provided in said body communicating with the chambered portion, governor mechanism in said chambered portion including fly-weights pivotally mounted on the end of said shaft and spring means non-rotatably mounted relative to said shaft and weights and 15 normally tending to move said weights to a retracted position, said shaft being arranged to be driven in timed relation with the member the speed of which is to be governed, and a control 20 valve plunger reciprocable in said shaft but held against turning therewith and operatively connected with the governor mechanism for movement back and forth in accordance with speed changes, said body having fluid passages therein 25 communicating with the bore for inlet and outlet of fluid to said valve, and said shaft having openings provided therein communicating with said passages and with respect to which the valve plunger is movable, said body having a drain collecting chamber therein and a fluid drain passage 30 thereto communicating with the governor chamber, and said shaft having a drain opening provided therein also discharging to said collecting chamber.

5. A structure as set forth in claim 4, including 35 a pair of gear recesses provided in said body one of which is concentric with the driven shaft, intermeshing pumping gears disposed in said recesses one of which is driven by said shaft, the other being an idler, a face plate detachably secured to the body closing the gear recesses, a hollow stub shaft in said body concentric with the idler gear recess and rotatably supporting the idler gear, said body and face plate having by-pass passages communicating with the bore of 45 said stub shaft and with the discharge side of the pumping gears, and a pressure relief valve controlling the flow of fluid through said by-pass.

6. A governor unit comprising fly-balls rotated in unison with a member the speed of 50 which is to be regulated, a tubular ported valve body turning with said fly-balls arranged to have the ports thereof communicate with the working cylinder and also with the source of pressure fluid supply and a drain, a single plunger valve 55 reciprocable within but non-rotatable with the ported body and arranged in one position to trap the fluid in the working cylinder but when moved in one direction to cause fluid injection into the cylinder and when moved in the other direction 60 to cause drainage of fluid from said cylinder, spring means for restraining the fly-balls, and means operatively connecting the plunger valve to the fly-balls and spring means so as to have the plunger valve moved positively in one direction by the fly-balls and impositively in the other direction by the spring means, and further so as to cause the plunger valve and spring means to remain stationary with respect to the relatively 65 rotating fly-balls and valve body.

7. In a governor controlled valve for regulating a hydraulic mechanism, centrifugally actuated members, a hollow drive shaft for said centrifugally actuated members having spaced ports therein, a valve stem slid- 70 able in but non-rotat- 75

able wth said drive shaft for controlling said valve ports, means operatively connecting said centrifugally actuated members with said valve stem permitting relative rotation therebetween, a spring opposing the action of said centrifugally actuated members, a pump, a conduit leading from the outlet side of said pump to said valve, a conduit between said valve and said hydraulic mechanism, and a drain channel from said valve 10 through said hollow governor drive shaft.

8. In a governor controlled valve for regulating a hydraulic mechanism, a casing having a governor chamber, a valve chamber, a pump chamber, and a pressure relief device chamber therein and channels leading from the exterior of said casing to said pump chamber, from said pump chamber to said valve chamber, and from said valve chamber to said pressure relief device chamber, a governor in said governor chamber, a hollow drive shaft for said governor extending through said pump chamber and said valve chamber having spaced valve ports therein, a valve stem in said hollow drive shaft operatively connected with said governor for controlling said valve ports, a pump gear on said drive shaft in said pump chamber, a spur gear in said pump chamber meshing with said pump gear, a tubular bearing pin for said spur gear extending at one end into said relief device chamber and hydraulically connected at its opposite end with said channel leading from the exterior of said casing to said pump chamber, a spring tensioned pressure relief device in said pressure relief device chamber for controlling the flow of fluid from said valve chamber through said pressure relief device chamber and said hollow bearing pin back to said pump, means connecting said pump chamber with a source of fluid under initial pressure, and a conduit between said valve chamber and 40 said hydraulic mechanism.

9. In a governor controlled valve for regulating a hydraulic mechanism, a casing having a governor chamber, a valve chamber, a pump chamber, and a pressure relief device chamber therein, and channels leading from the exterior of said casing to the pump chamber from the pump chamber to the valve chamber and from the valve chamber to the pressure relief device chamber, a governor in the governor chamber, a hollow drive shaft for the governor extending through the pump chamber and valve chamber having spaced valve ports therein, a valve stem in said hollow drive shaft operatively connected with the governor for controlling said valve ports, a pump gear on the drive shaft in the pump chamber, a spur gear in the pump chamber meshing with the pump gear, a tubular bearing pin for said spur gear extending at one end into the relief device chamber and hydraulically connected at its opposite end with the channel leading from the exterior of the casing to the pump casing, and a spring tensioned pressure relief device in said pressure relief device chamber for controlling the flow of fluid from the valve chamber through 65 the pressure relief device chamber and said hollow bearing pin back to said pump.

10. In a governor controlled valve for regulating a hydraulic mechanism, a casing having a governor chamber, a valve chamber and a pump chamber therein, and channels leading from the exterior of said casing to the pump chamber and from the pump chamber to the valve chamber, a governor in the governor chamber, a hollow drive shaft for the governor extending through 75 the pump chamber and valve chamber having

spaced valve ports therein, a valve stem in said hollow drive shaft operatively connected with the governor for controlling said valve ports, a pump gear on the drive shaft in the pump chamber, a spur gear in the pump chamber meshing with the pump gear, a tubular bearing pin for the spur gear providing a channel for fluid flow therethrough from the valve chamber back to the pump, and a pressure relief device for controlling fluid flow through said channel. 10

11. A governor mechanism comprising, in combination, a flyball head having flyball weights movably mounted thereon, a rotatable hollow drive shaft coupled to said flyball head in driving relation therewith, said hollow shaft having a port therein, means for supplying pressure fluid to the ported portion of said shaft, a valve plunger telescope within said shaft and reciprocable therein to control said port, said plunger being normally non-rotatable, and means for operatively connecting said flyball weights to said plunger to shift the same axially in response to changes in the speed of rotation of said drive shaft. 15

12. A governor mechanism comprising, in combination, a flyball head having flyball weights movably mounted thereon, a rotatable hollow drive shaft coupled to said flyball head in driving relation therewith, said hollow shaft having a port therein, means for supplying pressure fluid to the ported portion of said shaft, a normally non-rotatable valve plunger telescoped within said shaft and reciprocable therein to control said port, means for operatively connecting said flyball weights to said plunger to 30 shift the same axially in response to changes in the speed of rotation of said drive shaft, means including a nonrotatable speeder spring operatively connected to said plunger for yieldably urging the same axially in one direction, and 35 means manipulable while said shaft is rotating for adjusting the force exerted by said spring on said plunger. 40

13. A governor mechanism comprising, in combination, a rotatable flyball head, a plurality of flyball weights, means including a plurality of bell cranks for pivotally supporting said weights on said head with an arm of each of said bell cranks extending radially inward toward the axis of rotation of said head, a hollow tubular drive shaft coupled to said rotatable head in driving relation therewith, said shaft having a port therein, means for supplying pressure fluid to the ported portion of said shaft, a valve plunger telescoped within said shaft and reciprocable 50 therein to control said port, a thrust bearing including opposed races with anti-friction elements therebetween, one of said races being movable with said plunger and the other carried by said radially extending bell crank arms for operatively connecting said flyball weights and plunger, and a helical compression spring coaxial with said plunger and connected to one end thereof for yieldably urging the same axially in one direction, said spring and plunger being held 55 against rotation during normal operation of the governor. 60

14. A governor mechanism comprising, in combination, a pair of relatively rotatable fluid-control valve elements including a ported sleeve element and a plunger element telescoped therein, a rotatable flyball head connected to a rotatable one of said relatively rotatable valve elements for rotation therewith, means including a flyball weight carried by said head and operatively con- 70

- nected to the other of said valve elements for shifting the same axially with respect to one of said valve elements, means including a speeder spring yieldably urging said other valve element axially in one direction, and non-rotatable means acting on said spring and manipulable during relative rotation of said valve elements for adjusting said spring to vary the force exerted thereby on said other valve element.
15. In a governor mechanism for regulating a hydraulic device the combination of, a casing having a pump chamber, a drive shaft journaled in said casing and passing through said pump chamber, a governor connected in driven relation with said shaft, a fluid control valve operatively connected to said governor, a pump in said chamber embodying a pump gear on said drive shaft and spur gear in said pump chamber meshing with the pump gear, a stub shaft for said spur gear having a passage extending axially therethrough and communicating at its opposite ends with the inlet and outlet sides of said pump, and a pressure relief device for controlling the flow of fluid from said outlet side of said pump through said passage to the inlet side of said pump.
16. A governor mechanism comprising, in combination, a pair of relatively rotatable fluid-control valve elements including a ported sleeve element and a plunger element telescoped therein, a flyball head rotatable with one of said valve elements, a flyball carried by said head and op-

eratively connected to one of said valve elements for shifting the same axially with respect to the other element in response to changes in the speed of the rotatable element, a speeder spring coiled about the axis of said elements and yieldably urging said axially movable valve element axially in one direction, and non-rotatable means acting on said spring and manipulable during relative rotation of said valve elements for adjusting said spring to vary the speed controlling force exerted thereby.

17. A governor mechanism having, in combination, a rotatable hollow drive shaft rotatable with the part whose motion is to be regulated and having valve ports therein, a flyball head 15 rotatable with said shaft and carried by one end thereof, a normally non-rotatable valve stem reciprocable in said shaft and coacting therewith to constitute a valve, one end of said plunger projecting from said shaft through said flyball 20 head, an antifriction bearing having opposed race members, one actuated by said flyballs and the other coupled to said plunger, a non-rotatable speeder spring coiled about the axis of said plunger and disposed on the side of said head 25 opposite said shaft with one end coupled to said plunger to urge the latter in one direction against the action of said flyballs, and means manipulable while said shaft is rotating and acting on the opposite end of said spring to adjust the force 30 exerted thereby on said plunger.

ELMER E. WOODWARD.
